CROWN CAP FEEDING MEANS

John Wesley Hoffecker, Wilmington, Del., assignor to Continental Can Company, Inc., New York, N. Y., a corporation of New York

Application July 16, 1946, Serial No. 683,956

7 Claims. (Cl. 226—88.1)

1

The invention relates generally to crown cap feeding means and primarily seeks to provide novel agitator devices operable in crown cap feeding chute structures and effective to prevent jamming of the caps.

Although it is subject to more general adaptation, the invention is particularly adaptable for use in crown cap feeding mechanisms of the type disclosed in U. S. Letters Patent 1,932,529 issued to Berthold Nagy on October 31, 1933 wherein the crown caps are deposited indiscriminately into a hopper and, after being whirled about in rotary drums therein, are delivered into and through two gravity chutes having provision therein for righting the caps, that is turning such caps as may need turning to cause all caps to face in one direction. In the Nagy patent structure the caps finally are delivered into a single file delivery chute, being delivered thereinto directly from one of the two previously mentioned gravity chutes, and indirectly from the other gravity chute through a generally horizontally disposed connecting chute having a conveyor in its bottom wall effective to move the caps toward the juncture of said connecting chute, said one gravity chute and said delivery chute. In cap feeding mechanisms of the character stated considerable difficulty has been experienced in the jamming of caps at the chute juncture referred to and it is a purpose of the present invention to provide novel cap agitating means effective to prevent such jamming, and thus materially increase the daily output of the machine to which the caps are fed for subsequent operations thereon.

An object of the invention is to provide, in apparatus of the type stated and including a chute through which the caps are conveyed, a novel cap agitating means comprising a rotor having spaced flanges, and a spring projected agitator finger yieldably projecting beyond the periphery of the flanges and disposed to swing through a portion of the chute upon rotation of said rotor to engage caps therein in a kickback action effective to momentarily retard movement of the caps opposite said rotor.

With the above and other objects in view that will hereinafter appear, the nature of the invention will be more clearly understood by reference to the following detailed description, the appended claims, and the several views illustrated in the accompanying drawings.

In the drawings:

Figure 1 is a front elevation illustrating a crown cap feeder embodying the invention, parts being broken away and in section.

2

Figure 2 is an enlarged fragmentary sectional view showing the agitator in action kicking back a crown cap in the connecting chute.

Figure 3 is a detail vertical sectional view taken on the line 3—3 on Figure 2.

Figure 4 is an enlarged detail vertical cross section of the agitator rotor per se.

Figure 5 is an edge view of the rotor shown in Figure 4.

In the Nagy type of machine in which the improved agitating means is incorporated as an example of embodiment of the invention, the crown caps are deposited indiscriminately into a hopper 5 and fall onto an inverted V-shaped floor 6 which delivers them into one or the other of two axially aligned hollow drums 7 and 8.

The drums 7 and 8 are secured on the ends of a shaft 9 which is rotatable in a central housing bearing, and each shaft end has a pulley end member 10 or 11 secured thereon, one said pulley being driven by a belt 12 from any suitable power source (not shown). One of the drums 8 is equipped with a gear 13 which meshes with and drives a pinion gear 14 secured on a cross shaft 15 which is rotatably mounted in suitable frame bearings.

While being tumbled about in the drums, the crown caps are received uprightly, or on their edges, in a grooveway 16 formed between the end 30 of the respective drum 7 or 8 and the adjacent pulley end member 10 or 11 in the manner clearly illustrated at the right in Figure 1. Within the grooveway 16, the crown caps are supported by the respective stationary bar 17 or 18, and from 35 said grooveway the caps pass through openings in said bars into the uprightly disposed twister chute structures 19 and 20 wherein are included means for turning the caps so that all caps face in the same direction. While passing into the 40 chute structures 19 and 20, the caps are engaged by knurled disks 21 or 22 in order to prevent jamming of the caps as they enter the chute structures, and said disks are secured upon the cross shaft 15.

The two chute channels 23 and 24 of the gravity chute structure 20 deliver directly into a single file chute 25, but a knurled disk 26 preferably is mounted in position for having the periphery thereof project slightly into the chute 25 at the juncture of the channels 23 and 24 therewith in a manner for preventing jamming of the caps as they enter the single file chute 25. See Figure 2.

The two chute channels 27 and 28 of the gravity chute structure 19 deliver indirectly to the single file chute 25 through a generally horizon-

tally disposed connecting chute 29 having a conveyor chain flight 30 running over the floor thereof in position for engaging the crown caps and moving them along in the chute 29 in the manner clearly illustrated in Figures 1 and 2.

The chain passes over an idler sprocket 31 beneath the gravity chute structure 19, and over an idler sprocket 32 at the juncture of the channels 23 and 24 and the chutes 25 and 29. The position of the sprocket 32 is best illustrated in Figure 2, and from this figure and Figure 3 it will be apparent that said sprocket is secured on a sleeve 33 which is freely rotatable about a stud shaft 34 which is secured as at 35 on a bracket 36.

The sleeve 33 also is equipped with a pulley 37, and a belt 38 passes over the pulley 37 and over a pulley 39 on the shaft 40 which carries the knurled disk 26, thereby to impart rotation to said disk in a direction counter to the direction in which the crown caps pass into the single file chute 35.

The sleeve 33 also is equipped with a pulley 41 to which rotation is imparted through a twisted belt 42 from the pulley 43 which is secured on the previously mentioned cross shaft 15.

Still another pulley 44 is secured on the sleeve 33, and a belt 45 passes over said pulley and over a pulley 46 secured on a sleeve 47 which is freely rotatable about a stud shaft 48 secured as at 49 to the bracket 36.

It will be apparent by reference to Figures 2 and 3 of the drawings that the sleeve 47 is equipped with a pair of spaced, parallel flanges 50 which rotate in an accommodating opening formed in the top of the connecting chute 29 in the manner clearly illustrated in Figure 2. A detent finger 51 is rockably mounted between the flanges 50 on a cross pin 52, the finger being so disposed that its free end portion extends outwardly beyond the periphery of the flanges 50 as at 53. It will be apparent by reference to Figures 4 and 5 of the drawings that the extended or free end 53 of the finger 51 is provided with a cross pin 54 which extends over the flanges 50 and prevents retraction of the finger inwardly beyond the periphery of said flanges.

The other or inner end 55 of the finger 51 is recessed as at 56 to receive one end of a spring member 57 which is coiled about a cross pin 58 extending between the flanges 50, the other end 59 of said spring bearing against the sleeve 47 between the flanges in a manner for causing the spring 51 to constantly tend to hold the finger portion 53 in the extended position illustrated in full lines in Figure 4. The retracted position of said finger end portion is illustrated in dotted lines in said figure.

In the operation of the crown cap feeding means, the sleeve 47 and the disks 50 thereon are constantly rotated, and at each rotation of the sleeve the yieldably projected finger end portion 53 will swing through the connecting chute 29 directly above the sprocket 32 and engage crown caps passing through said chute in a manner for momentarily retarding them in the manner clearly illustrated in Figure 2. This momentary kickback action of the finger portion 53 serves to prevent jamming of the crown caps as they move with the caps from the channels 23 and 24 into the single file chute 25 by momentarily removing the pressure or weight of the succeeding caps in the channel 29 and thereby permitting the remaining caps in the other channels 23 and 24 to freely fall into position.

It will also be apparent that the rotation of

the knurled disk 26 in a direction counter to the direction of movement of the caps into the chute 25 contributes materially to the prevention of jamming of the caps at the juncture of the channels 23 and 24 and the chute 29 with the single file chute 25.

While one form of the invention has been shown for purposes of illustration, it is to be clearly understood that various changes in the details of construction and arrangement of parts may be made without departing from the spirit and scope of the invention as defined in the appended claims.

I claim:

1. In crown cap feeding means, a chute through which the caps are conveyed, a conveyor movable along one wall of the chute and having only frictionally engaging conveying contact with caps therein in a manner for conveying the caps uprightly on edge through the chute, and a rotary agitator disposed opposite said conveyor and having a spring finger swingable into the chute and in a direction opposite the direction of movement of said conveyor upon each rotation of the agitator in position for yieldably engaging edge portions of caps passing individually in processional order through the chute and momentarily retarding movement of said caps by said conveyor.

2. In crown cap feeding means, a chute through which the caps are conveyed, a rotor having spaced parallel flanges rotatable opposite the path of travel of caps through the chute, and an agitator finger pivoted between and having a portion thereof projected beyond the peripheries of said flanges in position for engaging and momentarily retarding progress of the caps through the chute as the rotor is rotated.

3. In crown cap feeding means, a chute through which the caps are conveyed, a rotor having spaced parallel flanges rotatable opposite the path of travel of caps through the chute, an agitator finger pivoted between and having a portion thereof projected beyond the peripheries of said flanges in position for engaging and momentarily retarding progress of the caps through the chute as the rotor is rotated, spring means for yieldably holding the finger in its projected position, and means for limiting retraction of the finger between said flanges.

4. In crown cap feeding means, a single file cap feeding chute having an uprightly disposed receiving portion, two uprightly disposed laterally spaced cap feeding chutes one of which is disposed to deliver directly into said single file cap receiving portion, a connecting chute disposed to deliver caps from the other of said two chutes to said single file cap receiving portion, means movable in said connecting chute and engageable with caps therein for aiding in the movement of the caps through said connecting chute, and an agitator rotor means operable opposite said movable means and adjacent the discharge of the connecting chute into said single file cap receiving portion and intermittently engageable with peripheral portions of caps moving through the connecting chute for momentarily retarding passage of the caps through said discharge.

5. In crown cap feeding means, a single file cap feeding chute having an uprightly disposed receiving portion, two uprightly disposed laterally spaced cap feeding chutes one of which is disposed to deliver directly into said single file cap receiving portion, a connecting chute disposed to deliver caps from the other of said two chutes

to said single file cap receiving portion, and agitator means operable adjacent the discharge of the connecting chute into said single file cap receiving portion for momentarily retarding passage of caps through said discharge, said agitator comprising a rotor and a yieldable finger projecting therefrom in position for engaging caps in the connecting chute as the rotor is rotated.

6. In crown cap feeding means, a single file cap feeding chute having an uprightly disposed receiving portion, two uprightly disposed laterally spaced cap feeding chutes one of which is disposed to deliver directly into said single file cap receiving portion, a connecting chute disposed to deliver caps from the other of said two chutes to said single file cap receiving portion, agitator means operable adjacent the discharge of the connecting chute into said single file cap receiving portion for momentarily retarding passage of caps through said discharge, said agitator comprising a rotor and a yieldable finger projecting therefrom in position for engaging caps in the connecting chute as the rotor is rotated, and a conveyor movable in the connecting chute for moving caps therethrough and passing about 25 a rotor disposed at the juncture of the connecting chute said one chute and said single file cap receiving portion, said agitator rotor being disposed opposite said conveyor rotor.

7. In crown cap feeding means, a single file cap feeding chute having an uprightly disposed receiving portion, two uprightly disposed laterally spaced cap feeding chutes one of which is disposed to deliver directly into said single file cap receiving portion, a connecting chute disposed to 30 35

deliver caps from the other of said two chutes to said single file cap receiving portion, agitator means operable adjacent the discharge of the connecting chute into said single file cap receiving portion for momentarily retarding passage of caps through said discharge, said agitator comprising a rotor and a yieldable finger projecting therefrom in position for engaging caps in the connecting chute as the rotor is rotated, 10 a conveyor movable in the connecting chute for moving caps therethrough and passing about a rotor disposed at the juncture of the connecting chute said one chute and said single file cap receiving portion, said agitator rotor being disposed opposite said conveyor rotor, and an agitator rotor disposed opposite the conveyor rotor at the juncture of said one chute with said single file cap receiving portion.

JOHN WESLEY HOFFECKER.
